UNITED STATES PATENT OFFICE.

WILLIAM G. WALKER, OF WASHINGTON, DISTRICT OF COLUMBIA.

DESIGN FOR A MATCH-BOX.

SPECIFICATION forming part of Design No. 23,061, dated February 13, 1894.

Application filed January 10, 1894. Serial No. 496,436. Term of patent 7 years.

To all whom it may concern:

Be it known that I, WILLIAM G. WALKER, a citizen of the United States, residing at Washington, in the District of Columbia, have 5 invented and produced a certain new and original Design for Match-Boxes; and I do hereby declare the following to be a description of the invention, reference being had to the accompanying drawings.

10 This invention relates to a new and original design for match boxes, and it consists in the peculiar shaping and arrangement of the parts thereof hereinafter referred to and claimed and illustrated in the accompanying drawings, wherein—

15 Figure 1 is a perspective of a match box embodying my design, and Fig. 2 is a side elevation thereof.

In the drawings A represents the match-20 holding receptacle having a straight back and sloping sides and front, converging inwardly toward the lower end. The back has a fanciful edging B on its upper edge extending above the sides, at the center of which is a 25 open space b. On the center of the back is a projection C extending out at right angles or in a horizontal direction.

D is the tray for the "burned" matches. This tray is rectangular and oblong and is located at the front of the base of the box. The 30 ends of the tray extend outwardly beyond the sides of the box. On the front of the box above the tray is a roughened surface E. The back of the box is extended below the tray as at F and has thereon a blank space in which 35 suitable characters may be placed. The sides of the extension F are curved and terminate at a point.

The essential features of the design are the shape of the match receptacle and the position and shape of the tray.

Having thus described the invention, what I claim as new, and desire to secure by Letters Patent, is—

The design for a match box substantially 45 as shown and described.

In testimony whereof I affix my signature in presence of two witnesses.

WILLIAM G. WALKER.
